UNITED STATES PATENT OFFICE.

HOWARD E. HARBAUGH, OF ROCKFORD, ILLINOIS.

MECHANICAL MOVEMENT.

SPECIFICATION forming part of Letters Patent No. 423,604, dated March 18, 1890.

Application filed July 1, 1889. Serial No. 316,199. (No model.)

To all whom it may concern:

Be it known that I, HOWARD E. HARBAUGH, a citizen of the United States, residing at Rockford, in the county of Winnebago and State of Illinois, have invented certain new and useful Improvements in Mechanical Movements, of which the following is a specification.

My invention relates to mechanism for producing an intermittently, rotary and oscillatory movement from a driving pulley driven continuously in one direction; and it consists of certain new and useful features of construction and combinations of parts specially devised to that end, all of which are herein-after fully described, and particularly pointed out in the claims.

Referring to the accompanying drawings, which form a part of this specification, Figure 1 is a front elevation of my improvement, having the parts thereof arranged to produce an oscillatory movement of the center or main shaft. Fig. 2 is a like view of the same, having the parts thereof rearranged to produce a rotary motion of the main shaft. Fig. 3 is a plan view of the machine as shown in Fig. 1. Fig. 4 is a horizontal section at line X-X of Figs. 2 and 5. Fig. 5 is a rear elevation. Figs. 6, 7, and 8 are vertical sections at lines X-X', X-X², and X-X³, respectively, of Fig. 5. Figs. 9 and 10 are vertical sections at line X⁴-X⁴ of Fig. 3 of the upper portions of the pulleys there shown. Figs. 11 to 15, inclusive, are detailed views showing two cams, which are intimately connected with the operations of changing the movement of the machine from rotary to oscillatory, and vice versa. These last-mentioned views also illustrate the different positions assumed by the cams while performing their allotted functions and the parts co-operating therewith.

Like letters of reference indicate corresponding parts throughout the several views.

A is a frame for operatively supporting the various parts of the mechanism, and may be of any suitable form and construction.

A' is a tubular bearing in the frame A.

A² is a bearing projecting from the frame A. A horizontal opening A³ extends through

the bearing A² and frame A to admit other parts.

A⁴ is a boss projecting from the frame A.

A⁵ is a horizontal opening extending through the boss A⁴ and frame A.

B is a pinion provided with a revoluble sleeve B', which is mounted in the bearing A' and serves as a bearing for said pinion.

C is a main shaft of the machine, and is inserted through the pinion B and sleeve B', which form a bearing therefor.

C' is a pinion fast to the shaft C.

C² is a beveled gear-wheel for transmitting power from the shaft C, to which it is fast. This wheel is not shown in Figs. 1 and 2, as it would hide the pinions there shown.

D is a pulley fast to the revoluble sleeve B'.

D' D² are lugs for operating cams, to be described hereinafter.

E is a bushing, which is rigidly connected with the shaft C by clamping it against the shoulder C³ thereon by means of the nut C⁴.

E' is an annular flange projecting from the outside of the bushing E and having radial slots E² opening outward therefrom. The slots referred to are clearly shown in Figs. 9 and 10.

F is a pulley loose on the bushing E.

F' is a detent located on the inner side of and parallel with one of the spokes F² of the pulley F.

F³ is a stud projecting from the spoke F² into a longitudinal slot F⁴ in the detent F'.

F⁵ is a spring for actuating the detent F', which, when normal, connects the pulley F, through the bushing E, with the shaft C, as shown in Fig. 9, except that the shaft C is not there shown. By inserting the pin F⁶ through the holes F⁷, F⁸, and F⁹ in the spoke F², detent F', and one of the spokes of the pulley D the pulley F may be disengaged from the shaft C and caused to connect with the revoluble sleeve B' through said pulley D, as shown in Fig. 10. The outer end of the pin F⁶ has a handle formed thereon, by means of which the machine may be operated by hand, if desired.

G is a carriage capable of lateral reciprocation, as indicated by the dotted lines Y in

Figs. 3, 4, and 5. Obviously the carriage might be arranged to reciprocate in any of the well-known ways, but I prefer to pivot it by means of the bolt G' to the frame A.

5 G² G³ are tubular bearings inserted through and rigidly connected with the carriage G.

H is a sector-gear fast to the axle H', which is inserted through the tubular bearing G², wherein it is retained by the sector-gear H and collar H², which is also fast to the axle H'.

I is a gear-wheel mounted on the bearing A².

I' is another gear-wheel fast to the axle I², which is inserted through the tubular bearing G³, wherein it is retained by the gear-wheel I' and the collar I³, which is fast to the axle I².

I⁴ is a pin projecting from the gear-wheel I through the slot I⁵ in one of the spokes of the gear-wheel I'. The connection shown evidently requires the gear-wheels II' to revolve together at all times.

The sector-gear H and gear-wheel I' are connected with the carriage G through the tubular bearings G² G³ and axles H' I², and therefore participate in the lateral reciprocations of the carriage G, already referred to, the openings A³ A⁵ in the parts A A² A⁴ freely permitting lateral reciprocation of the parts extending through said openings and their connections.

J is a pitman, which is pivotally connected with both the sector-gear H and the gear-wheel I' by means of bolts J' J².

K is a tubular bearing extending through and rigidly connected with the frame A.

K' is a rocking sleeve inserted through the tubular bearing K, in which it may be oscillated. The end K² of the rocking sleeve K' is re-enforced by increasing the diameter thereof, and provided with a transverse bifurcated stud K³, which has a cam K⁴ set and secured therein by the rivet K⁵.

K⁶ is a collar fast to the rocking sleeve K'.

L is a rod inserted through the rocking sleeve K', wherein it freely slides.

L' is a cam integral or rigidly connected with one end of the rod L. The cam L' has a hole L² therein, which admits a pin K⁷, which projects from the stud K³. The pin K⁷ compels the cam L' to oscillate simultaneously with the cam K⁴ and at the same time allows it to slide back and forth with the rod L, to the end of which it is fast.

The cams K⁴ L' have two motions, as shown in Fig. 11, limited by the pins A⁶, and move simultaneously. The cam L' also has two motions independently of the cam K⁴, as shown in Figs. 12 and 15. The function of the cam K⁴ is to reciprocate the carriage G, thereby intermittently meshing the sector-gear H and gear-wheel I with the pinion C', according as it is desired that the main shaft C shall oscillate or rotate. The office of the cam L' is to alternately reverse the movements of the cam K⁴.

The rod L has, in addition to the longitudi-

nal-reciprocating motions already mentioned, oscillating reciprocating motions synchronous and identical with the rocking sleeve K', with which it is connected through the cam L' and pin K⁷.

Power is applied to the free end of the rod L for operating the cam L', the rocking sleeve K', and the cam K⁴, connected therewith. The necessary power and motions for operating the rod L may be imparted thereto through a pattern-wheel having operative connection with the free end thereof, or in any other suitable manner, and it has not been deemed necessary or desirable to show any particular mode of operating it.

In order to facilitate an understanding of the combined operations of the entire machine, the operations of the different sets of parts comprising the same will be given. At

85 attention will first be directed to the movements of the carriage G and the parts producing those movements. Supposing the pulley D to be disengaged from the pulley F, the carriage G and the cams for operating the same

90 to be in the positions shown in Figs. 1, 5, and 11, and the sector-gear H to be meshed with the pinion C', revolving the pulley D, and the lug D' (see Fig. 13) will engage with the upper portion of the cam L' and throw it and the cam K⁴ to the positions indicated by the dotted

95 lines in Figs. 5 and 11 and shown by solid lines in Fig. 12, the result of which operations will be to move the carriage G to the position indicated by dotted lines Y in Fig. 5 and shown in 100 solid lines in Fig. 4, and mesh the gear-wheel I' with the pinion C'.

At the proper time thereafter the rod L will slide backward, carrying the cam L' to the position indicated by dotted lines in Fig. 12 and shown in solid 105 lines in Fig. 14. The next revolution of the pulley D will cause the lug D' to engage with the lower portion of the cam L' (see Fig. 14)

110 and throw it and the cam K⁴ to the positions shown by solid lines in Fig. 11, except that the cam L' is in contact with the cam K⁴ in

115 Fig. 11, and indicated by the dotted lines Z in Fig. 15. The rod L then slides to its original position, carrying the cam L' to the position shown in Figs. 11 and 13. The series of move-

120 ments just detailed will leave the carriage G, the cams K⁴ L', and the rod L in the same positions as at the outstart, and the gear-wheel I' will have been unmeshed from and the sector-gear H remeshed with the pinion C'.

Obviously the movements of the rod L may be so timed as to allow any desired interval of time to elapse between each reciprocation or movement of the carriage G and the parts moving therewith. The gear-wheel 125 I' being mounted on an axle I², which admits of lateral reciprocating motion, the bearing A² of the gear-wheel I may evidently be concentric with the latter, as shown in Fig. 1, or eccentric therewith, as shown in Fig. 2, 130 but both gear-wheels, being connected by the pin I⁴, must necessarily always revolve to-

gether. With the sector-gear H meshed with the pinion C', as shown in Fig. 1, power applied to the pulley D and transmitted through the sleeves B', pinion B, gear-wheels II', and pitman J to the sector-gear H will oscillate the latter and the main shaft C so long as the connections just enumerated are maintained. Permit the connections and application of power to remain the same as last stated except that the carriage is moved so as to cause the sector-gear H to unmesh from and the gear-wheel I' to mesh with the pinion C', as shown in Fig. 2, the main shaft C will then rotate as long as the connections and conditions just stated remain the same, and the sector-gear H will oscillate as an idler. As has already been stated, power applied to the pulley D will oscillate or rotate the main shaft C, according as the pinion C' is meshed with the sector-gear H or gear-wheel I'. Power applied to the pulley F while it is connected with the main shaft C, as shown in Fig. 9, will also cause the latter to rotate; but an oscillatory movement of said shaft C cannot be produced by applying power to the pulley F, as said pulley must participate in all the oscillatory movements of the main shaft C. There is, however, an advantage to be gained in driving the shaft C by means of power applied to the pulley F when rotary motion is required, for while the periphery of the gear-wheel I' and the pinion C' are as three to one a complete revolution of the gear-wheel I' produces, when transmitting motion through the pitman J and sector-gear H, but two oscillatory revolutions of the pinion C' and its shaft C, while the same speed transmitted directly from the pulley F to the shaft C would rotate it three times. The pinion C', sector-gear H, and gear-wheel J' are so adapted and arranged with reference to each other in point of speed that either of the two latter may engage with and disengage from the former while the machine is in full operation, the sector-gear when unmeshing continuing its engagement with the pinion until the gear-wheel I' is sufficiently meshed therewith to propel it, and vice versa. The movements of the machine are thereby rendered constant, and alternately or intermittently rotary and oscillatory movements may be obtained from the main shaft C, at the will of the operator. Obviously the pinion C' might be arranged to travel between the sector-gear and gear-wheel I' and alternately mesh with the same and produce like results without departing from the spirit and scope of my invention. Obviously a gear-wheel or other equivalent toothed device might be substituted for the sector-gear H without changing the character of my invention. The oscillatory and rotary motions of the main shaft C may be transmitted to any suitable mechanism through the bevelled gear-wheel C².

This machine may be used whenever intermittently oscillatory and rotary movements

are required, and will be found to be especially useful in connection with knitting-machinery requiring the two movements just referred to.

I claim—

1. A gear C', capable of being transferred directly from engagement with the teeth of a rotating gear I' into engagement with the teeth of an oscillating gear H, and vice versa, all three of said gears being combined substantially as and for the purpose specified. 70

2. In combination, a shaft suitably mounted, a pinion fast thereto, the sector-gear and a gear-wheel so mounted with reference to each other and said pinion as to be capable of alternately meshing therewith singly, and the pitman connecting the sector-gear and gear-wheel together, substantially as specified, and for the purpose set forth. 80

3. In combination, the main shaft, a pinion connected therewith, the sector-gear and gear-wheel so arranged with reference to each other and said pinion as to be capable of alternately engaging therewith while said sector-gear, gear-wheel, and pinion are in motion, and the pitman connecting the sector-gear and gear-wheel together, substantially as and for the purpose set forth. 90

4. In combination, the main shaft, the pinion secured thereto, and the sector-gear and gear-wheel so arranged with respect to each other and the pinion that neither the sector-gear nor gear-wheel can become disengaged therefrom without the other first engages therewith, the sector-gear and gear-wheel having a pitman-connection, substantially as and for the purpose set forth. 95

5. In combination, the main shaft, the pinion fast thereto, the carriage capable of reciprocation, and the sector-gear and gear-wheel so mounted on said carriage as to also be capable of sufficient reciprocation to suffer them to alternately mesh with said pinion, substantially as and for the purpose set forth. 105

6. In combination, the carriage G, capable of lateral reciprocation, the cam K', arranged to engage with and laterally reciprocate said carriage, and the cam L', for operating the carriage-reciprocating cam, substantially as 110 and for the purpose specified.

7. In combination, the pinion B, provided with a revoluble sleeve, the main shaft inserted through and journaled in said pinion and sleeve, the pinion C', fast to the main shaft, the sector-gear and gear-wheel adapted to alternately or simultaneously mesh with the pinion C', the gear-wheel I, meshing with the pinion D, and the reciprocating carriage wherewith the sector-gear and gear-wheel are connected by means of axles, substantially as specified, and for the purpose set forth. 120

8. In combination, a suitable frame, the reciprocating carriage pivotally connected therewith, the pinion B, provided with a sleeve, the main shaft mounted in said sleeve,

the gear-wheel I, mounted on a bearing fixed to the frame, the gear-wheel I', operatively connected with said reciprocating carriage and being capable of concentricity or eccentricity with the gear-wheel I, the sector-gear 5 operatively connected with the reciprocating carriage, the cam K⁴, for reciprocating said

carriage, and the cam L', for operating the cam K⁴, substantially as and for the purpose set forth.

HOWARD E. HARBAUGH.
